W. A. BURT.
TYPOGRAPHER.

Patented July 23, 1829.

W. A. Burt, July 23, 1829.

This patent discloses the actual construction of a type writing machine for the first time in any country.

The type are arranged on the under side of a segment carried by a lever pivoted to swing vertically and horizontally.

The desired character is brought to the printing point by moving this lever horizontally to a position over the same character in the index, and the impression is made by then depressing the lever.

Several styles of type may be used and they are arranged in two rows on the lever; these rows of type can be shifted on the lever to bring either one to the printing point.

The paper is carried on an endless band which travels cross-wise of the machine, and this band is moved for letter space by the impression lever every time said lever is depressed to print.

The line space is made by shifting the frame carrying the printing mechanism toward the front or rear of the machine, the paper remaining stationary.

Ink-pads are located at each side of the impression point, and all the type except the one in printing position are inked every time the impression lever is depressed.

A dial is provided which indicates the length of paper in inches which has passed the printing point in printing each line, and as the operator knows the width of the paper being used the time to stop printing at the end of the line is indicated.

The United States of America.

TO ALL TO WHOM THESE Letters Patent SHALL COME

Whereas William A. Burt a citizen of

the United States hath alleged that he hath invented a new and useful improvement
being a machine for printing styled by him the "Typewriter"

which improvement he states has not been known or used before his application hitherto, and
that he doth verily believe that he is the true inventor or discoverer of the said improvement, hath
paid into the treasury of the United States the sum of thirty dollars, delivered a receipt for
the same, and presented a petition to the Secretary of State signifying a claim of the invention
exclusive property in the said improvement, and praying that a patent may be granted for that
purpose. There are therefore to grant according to law, to the said William A. Burt
his heirs, administrators or assigns, for the term of fourteen years from the day hereof, the right
of using, one thousand eight hundred and twenty nine, the full and entire right and
liberty of making, constructing, using and vending to others to use, the said improvement,
a description whereof is given in the words of the said William A. Burt, himself
in the schedule hereto annexed, and is made a part of these presents.

In Testimony whereof, I have caused these Letters to be made Patent and the
Seal of the United States to be affixed thereto affixed.

GIVEN under my hand at the City of Washington, this twenty-third day
of July in the year of our Lord one thousand eight hundred
and twenty-nine, and of the independence of the United States, in the
fifty-fourth.

Andrew Jackson

BY THE PRESIDENT

Wm. B. Brewster, Secretary of State

City of Washington. TO WIT.

I DO HEREBY CERTIFY That the foregoing Letters Patent were deli-
vered to me on the twenty-third day of July in the year of our
Lord one thousand eight hundred and twenty-nine, to be examined.
I have examined the same, and find them conformable to law and
do hereby return the same to the Secretary of State, within fifteen days
from the date aforesaid, to wit on the twenty-third day of July
in the year of our said.

Sept 1855.

Wm. H. Hunt and George, Attorney general of the United States
